14 Claims. (Cl. 175—41.5)

With electrical variable condensers and the like, for instance, such used in radio receiving sets, in many cases the rapid and extremely accurate adjustment of a definite value of the capacity is called for. For that purpose it has been suggested in known rotary or variable condensers to combine a rough adjusting system with a system for fine adjusting, electrically connected in parallel. Generally, the manipulation of the 10 movable fine adjusting plate is effected through a special handle co-ordinated to the knob for rough adjustment. However, arrangements have already been suggested, in which the sets of plates or segments of the condenser for rough 15 and fine adjustment may be manipulated by means of a single adjusting knob, which was rendered possible by the provision of a no-load coupling or lost motion connecting device which will admit of the adjustment of the set of plates for fine adjustment within the limits of its play, without causing a change of adjustment of the 20 set of plates for rough adjustment effected previously by means of the same adjusting handle.

These known arrangements with no-load couplings, however, did not gain any practical importance. This may be attributed on the one hand to the circumstance, that the play of the no-load coupling employed was not sufficiently small, in order to effect the adjustment of the 25 condenser in a rapid and simple manner, as in the case of the ordinary rotary condensers without fine adjustment.

Moreover, through the large play in coupling present with the known arrangements, the practical manipulation of the condenser, if the latter was employed in radio apparatus, was rendered difficult to such an extent, that the industry declined to make use of such condensers, while for the fine adjustment transmission gearing was employed to a growing extent. On the other hand, the known adjusting devices with a special coupling for the rough and fine adjustment by manipulation of a single knob, were not as yet sufficiently simple in construction and 45 required much space.

As regards the known rotary condensers with transmission gearing, it is possible however to obtain a very accurate adjustment of the operating value desired each time by making use of a 50 high ratio of gearing. But, besides, the complicated mode of execution dependent on a high ratio of gearing, there is the drawback, that with manipulation by means of a single knob a great many rotations of said knob are necessary, in order to pass from one condenser adjustment to another more remote condenser adjustment. Therefore it was again endeavored to choose the 55 ratio of gearing with such arrangements not too great at the expense of the accuracy of adjustment, and a compromise was made upon choos-

ing the magnitude of such ratio, which will make allowance for the two oppositely directed moments, without however fully satisfying the desires, neither in the one direction nor in the other.

In order to facilitate the fine adjustment of a condenser without the use of a special transmission device, adjusting devices with a no-load coupling, as already mentioned, have been suggested.

The aggravation of the manipulation of the condenser caused by the large play in coupling with known devices of this type, above all consisted in that with these arrangements the rapid adjustment to a definite operating value with the aid of a scale is impeded and that certain prescriptions had to be observed during adjustment. Thus with the use of known adjusting devices with a large coupling play in radio receiving sets with a station scale a definite station 10 can only be selected rapidly and easily, if the said station scale has been gauged for stations 15 simply by advancing the adjusting pointer, whereby the selection of a certain station with the aid of the scale can be effected only by a 20 forward rotation. In the same manner, of course, also the calibration by returning the adjusting pointer backward could be carried through, whereby the selection of a certain station on the scale could be effected only by a 25 reverse rotation. By making use of two scales, one 30 of which is calibrated for forward rotation and the other one for reverse rotation, the zeroing prior to each new rough adjustment, during 35 which the direction of rotation must be changed over the direction of rotation of the preceding rough adjustment, could be dispensed with, however, the manipulation of a radio apparatus by means of two scales would be rendered exceedingly 40 difficult.

The invention has for object to obviate these deficiencies of the known adjusting devices with no-load coupling and with a rough and fine adjusting arrangement operated by a single adjusting knob.

According to the invention the magnitude of the adjusting range limited by stops or the like with adjusting devices, particularly with electrical rotary condensers having a coupling, which will render possible the manipulation of a rough and fine adjusting member or system by means of a single adjusting knob, is chosen so small, namely with a rotary device about ten angular degrees and less, that the immediate adjustment of the desired value of operation, particularly with the aid of an adjusting scale, is rendered possible during the advance and return movement of the adjusting knob in an equally simple manner.

Through the choice of a very small range of 50

movement of the fine adjusting member, by the provision of stops, for instance the flanks of a no-load coupling, a manipulation of the fine adjusting member is obtained, which is just as simple as that with the known ordinary adjusting devices without any special coupling and fine adjustment. It must be considered in this respect, that the setting of an adjusting device with the aid of an adjusting scale to a definite value on the 10 scale will be effected in general only in a more or less crude manner, since such adjustment is dependent on numerous influences, as for instance, lack of practice, parallax, rapidity of effecting the adjustment, distribution of shades 15 with unfavorable illumination and the like.

As is well known, the adjustment of a radio receiving set through the commonly technically untrained listener is effected in such a manner, that in the first place the desired station is selected 20 with the aid of the station by means of the eye in a relatively short time.

But such adjustment is effected only in a rather crude manner, whereupon fine adjustment is obtained with the aid of the ear by carrying out 25 slight reciprocating movements about the point chosen by rough adjustment. A purely optical adjustment simply with the aid of the eye by means of the station scale would be futile with a radio receiving set for the reason, that very seldom a quite precise agreement of the mark of the scale allotted to a distinct sending station will be present at this junction with the best audibility 30 of the sending station. There may occur deviations amounting to several angular degrees. For 35 that reason it is absolutely necessary to carry out adjustment with the aid of the eye only quite crudely and to effect fine adjustment through the ear subsequently. Here very often, particularly with adjusting devices having a small ratio of 40 gearing, the selection among the special adjustments lying frequently rather close to the rough adjustment, is effected subsequent to the rough adjustment through the eye simply through the ear only, because the desired sending station can 45 be obtained in this manner more easily and rapidly than through a purely optical selection. But if the range of inaccuracy of adjustment caused by the adjusting operation as such coincides with the small range of inaccuracy remaining yet 50 through the reduced play of the coupling, or if the former will constitute a substantial portion thereof, any injurious effect through the play of the coupling cannot occur at all, on the contrary the practical use of the improved adjusting device 55 is just as simple as that of the known adjusting devices without special coupling and consequently also without the possibility of fine adjustment.

Therefore, with the rather minute play of the 60 coupling of an adjusting device with a no-load coupling according to the invention advantages are obtained, which will not be present with the known arrangements of this type having a large play of the coupling.

Beyond this, the invention has for its object 65 the suitable construction of an adjusting device with adjusting knob for the automatic rough and fine adjustment carried out in the manner described. This improved construction is obtained according to the invention in that the member for fine adjustment of the adjusting device is driven in the course of the power transmitting driving-parts by way of a friction coupling and 70 that the motion of said member is being limited 75

by means of two stationary stops. From this follow various modes of construction.

On the accompanying drawings the invention is illustrated by way of example and

Figure 1 is an electrical rotary condenser according to the invention partly in section, as seen from the side; 5

Figure 2 is a rear view of said condenser;

Figure 3 illustrates the scale of said condenser on a reduced scale; 10

Figure 4 represents a notched disc of said condenser, likewise on a reduced scale;

Figure 5 is a diagrammatic view of another modification of the condenser according to the invention; 15

Figure 6 represents a portion of the transmission gear of the modification according to Figure 5;

Figure 7 is a further modification of a condenser according to the invention without transmission gear, as seen from the side, partly in section; 20

Figure 8 is a rear view of the modification according to Figure 7; and

Figure 9 is a rotary condenser according to the invention with transmission gear. 25

With the modification of the improved rotary or variable condenser illustrated in Figure 1 the stationary set of plates or segments carried by the support 1 of the condenser 2 for rough adjustment is designated by 3 and the movable set of plates by 4. The movable plates or segments 4 are mounted on a hollow shaft 5 within which a spindle 6 is journaled. On the front end of the spindle 6 is mounted a disc 7, which is in frictional engagement with a disc 8 of smaller size, which latter is actuated by a turning knob 9. The disc 7 is provided with a hand or pointer 10 moving in front of a scale 11, as follows particularly from Figure 3. Upon the rearward extremity of the spindle 6 is arranged a short sleeve 12, being rigidly connected with the spindle 6 by means of a set screw 13 with sunk head. In contradistinction the hollow shaft 5 of the rotor is adapted to easily rotate about the spindle 6 30 and it is provided on its rear end with an extension 14 which engages with play a slot 15 in the sleeve 12, so that a no-load coupling 16 is produced. 35

On the sleeve 12 is arranged in frictional connection a further sleeve 17, from which a flat tongue 18 projects, which is provided on its surface with an insulated coating 19, which cooperates capacitatively with a counter-layer or coating 20 forming a condenser 21 for fine adjustment. The counter-coating 20 is formed in a simple manner by one shank of an angular piece 22 of sheet metal, the other shank 23 of which is secured to the support 1 of the condenser for rough adjustment 2 by means of one of the known nuts 24, serving for the assemblage of the stator. The movement of the tongue 18 is limited through a stop pin 25 of insulating material. In order to prevent an electrical contact of both the electrodes 18 and 20 of the auxiliary condenser, 60 a projecting non-conductive limiting pin 26 is provided on the electrode 20. 65

Figures 1 and 2 therefore illustrate a rotary condenser, which forms the combination of an ordinary rotary condenser 2 as rough adjusting system, the plates 3 and 4 of which are moved parallel to each other, with a condenser 21 for fine adjustment, the plates 18, 20 of which are moved in a direction perpendicular to their superficial dimensions. 70

The arrangement is such, that the condenser 21 for fine adjustment is actuated in the course of the power transmitting parts: knob 9, small driving disc 8, large driving disc 7, spindle 6, 5 sleeve 12, sleeve 17, tongue 18, condenser electrode 18 by way of a friction coupling 27 formed by the telescoped sleeves 12 and 17 and the movement of the electrode 18 for fine adjustment is limited by the stationary stops 25, 26, which are rigidly 10 held by the support 1 of the condenser 2 for rough adjustment.

Besides, there is provided with the described modification according to Figure 1 in the course of the power transmitting driving-parts 9, 8, 7, 15 6, 12, 5 for the rotor 4 of the condenser 2 for rough adjustment, which are actuated by the same knob 9, the no-load coupling or lost motion connecting device 16.

With multi-condensers for multi-circuit receiving sets for wireless telephony the described arrangement may be multiplied and the spindle 6 may be continuous, as such is indicated by broken lines in Figure 1.

Furthermore, a disc 28 may be mounted on 25 the rotor shaft 5 of the condenser 2 for rough adjustment (Figure 1), as such is illustrated in detail in Figure 4. Said disc may be provided with notches distributed thereon in correspondence with the capacities to be selected or with the 30 sending stations the signals of which are to be received respectively, which notches are engaged during the rotation of the disc by a positioning pin 31 being subjected to the action of a spring 30, without however completely hindering the 35 rotation. The said notches facilitate the rapid adjustment of the condenser. They will define certain capacities of the condenser 2 for rough adjustment, while through the fine adjustment with the aid of the auxiliary condenser 21 intermediate stages may be selected, which are 40 approximate to or lie between the values obtained by rough adjustment.

The sleeve 12 is provided in the modification 45 illustrated in Figure 1 with a steep thread 32 while the sleeve 17 slipped over it, is formed as appurtenant screw-nut.

By this an axial movement of the sleeve 17 is obtained at the same time with the rough adjustment, which will effect a parallel displacement 50 of the electrode 18 of the auxiliary condenser 21 in respect of its counter-electrode 20, so that these electrodes will register more or less. The described construction in an extremely simple manner allows a fine adjustment of constant sensitiveness with regard to the value of 55 the coarse adjustment selected each time. The final adjustment being obtained thereafter by slight turning movements of the knob 9 in either direction in the manner explained already.

The magnitude of the play of coupling of the 60 no-load coupling 16 with the modification according to Figures 1 to 3 is chosen rather small. Figure 3 illustrates the rather acute angle of rotation α , admitted by the play of the no-load 65 coupling during a rotary movement up to the contact of the flanks of said no-load coupling each time. Owing to this slight play of coupling the selection of a definite rough value of capacity with the aid of the adjusting scale 11 is rendered 70 possible in an equally simple manner both by turning the knob 9 to the right and left hand side and the manipulation of the novel condenser is just as simple as that of the ordinary condensers, in which there is not made any provision 75 for fine adjustment.

The mode of operation of the novel rotary condenser according to Figures 1 to 3 may be more fully explained in employing it with a receiving set for wireless broad-casting, for which condensers of this class are preferably adapted and intended.

When selecting a certain station the knob 9 is turned until the pointer 10 (Figures 1 and 3) reaches the desired spot on the scale 11. During such rough adjustment simply the rotor 4 of the 10 condenser 2 for rough adjustment is moved, while the electrode 18 for fine adjustment of the auxiliary condenser 21 abuts against one of the stops 25 or 26 and remains inoperative without hindering the rotary movement of the set of 15 plates 4 for rough adjustment thanks to the frictional connection 27. Subsequent to rough adjustment now by a slight reciprocatory turning of the knob 9 by gradually decreasing pendulum movements about the position of the pointer selected at first in a crude manner, the selection of the desired receiving value is carried through, until optimum reception of the signals is obtained. Here the no-load coupling 16 will come into the action, which causes a variation of the 20 adjustment of the condenser 21 for fine adjustment. By operating the rotary condenser in the manner customary with the adjustment of receiving sets, the fine adjustment is automatically effected subsequent to each desired rough adjustment. 25

If an adjusting device with transmission gear is used, a special no-load coupling may be dispensed with when the said transmission gear possesses a lost motion run or such is applied to 30 it. In Figure 5 a rotary condenser 33 is illustrated, the rotor 44 of which mounted on the shaft 43 is driven by way of the transmission gears 34, 35. The intermeshing gears 34, 35 represented once more in Figure 6 in front view offer 35 a certain lost motion run through a play existing between the teeth.

The driving shaft 36 for the small gear 34, on one extremity of which the operating knob 37 is mounted, carries on its opposite extremity a 40 tongue 38 by forming a friction coupling 39 in frictional connection with it, which in the same manner as described above, will form with the counter-electrode 40 an auxiliary condenser 41, which serves for fine adjustment. The deviation 45 of the tongue 38 is limited on the one hand by the counter-electrode 40 and on the other hand by a stop pin 42. The mode of operation of the modification according to Figure 5 should be obvious at once, since the above explanations in respect 50 of the mode of operation of the condenser according to Figures 1 to 3 will also apply to this case. When using the invention with adjusting devices the driving means of which operate with play or have elastic flexibility, i. e. have a driving shaft which warps, that is to say, when employing the invention in connection with adjusting devices the drive of which has mechanical allowances, profitable use may be made of such allowances as, according to the invention, they cannot exert any disturbing influence on the fine 55 adjustment, whereas, in contradistinction to this, hitherto such mechanical allowances were highly injurious to the fine adjustment of condensers used in wireless telephony. 60

Figures 7 and 8 show a rotary condenser 45 of the customary mode of construction in side and rear view, in which simply the shaft 47 driven by the turning knob 46 is somewhat longer at its rear end than usually. Over this extremity 75

is slipped the tongue 48, which is bent below to form a spring sleeve 49 (Figure 8). Through the resiliency of the sleeve 49 a good frictional fitting is obtained providing a friction coupling 50 between the shaft 47 and the sleeve 49.

At its upper end, the tongue 48 is provided with an electrode 51, which cooperates capacitively with a counter-electrode 52 forming an auxiliary condenser 53. Said counter-electrode 52 is carried by one shank of an angular member 54, the other shank 55 of which serves as attaching means to the frame of the condenser 45. The contact of the two electrodes 51 and 52 is prevented by an insulating pin 56 and the retrograde movement of the tongue 48 is limited by a stop pin 57 of insulating material. The pins 56 and 57 are located closely opposite so that the maximum sway of the tongue 48 is only very small, in the example illustrated below ten angular degrees. The chief condenser 45 and the auxiliary condenser 53 are connected electrically in parallel in known manner.

With the modification according to Figures 7 and 8 is arranged in the course of the power transmitting driving-parts for the electrode 51 for fine adjustment a friction coupling 50, but any no-load coupling is missing here. However the arrangement in this instance is such that upon manipulating the adjusting knob 62, which will cause an increase of the capacity of the condenser 45 for rough adjustment by turning the set of plates 58 of the rotor in the direction of the arrow shown in Figure 8, the movement of the electrode 51 for fine adjustment takes place in the sense of the arrow shown there in a direction, in which the capacity of the auxiliary condenser 53 will decrease, since the electrode 51 of the latter will recede from its counter-electrode 52. At an opposite turning of the adjusting handle 46 the same applies in a reverse manner.

Through this arrangement it is possible that after having effected the rough adjustment of the device to a definite operating value during fine adjustment within the range of the sway of the tongue 48 defined by the limiting pins 56, 57, the movement of the condensers 45 and 53 respectively for rough and fine adjustment is effected in a manner, in which the rough and fine value of the capacity will change in the reverse sense and both values will partly compensate one another. The compensation of the capacity is chosen so great, that the change of the capacity still remaining here during the turning within the small range for fine adjustment defined by the stationary stops 56, 57 (Figure 8), will just render possible a commodious fine adjustment to all practically obtainable fine values such as for tuning wireless receiving sets.

With the arrangement according to Figure 9 the principle of fine adjustment through partial compensation of the change of capacity of the condenser for rough and fine adjustment described above, within the small range for fine adjustment again defined by means of stationary limiting agents, is likewise resorted to. In this instance again a condenser is concerned having a transmission gear. The rotor 61 of the condenser 60 is driven by the knob 62 by way of the shaft 63, and the frictionally engaging discs 64 and 65. On the right hand end of the shaft 63 is mounted again a tongue 67 in frictional connection by forming a friction coupling 66, said tongue carrying an electrode 68, which will capacitively cooperate with the counter-electrode 69. The two electrodes 68 and 69 again form an auxiliary con-

denser 10. The electrical connections of the two condensers 60 and 70 electrically connected in parallel, are not shown, since these are obvious. The modification according to Figure 9 has the advantage over that according to Figure 7, in that in consequence of the power transmitting device 64, 65 upon manipulating the adjusting knob 62, the rotary movement of the electrode 68 serving for the fine adjustment is greater than the rotary movement of the rotor 61 serving for rough adjustment. The mode of operation of the condenser according to Figure 9 is obvious in consideration of the explanations rendered above, particularly in respect of Figure 7.

The arrangement of the novel adjusting device 15 may be effected in a manner varying from the specification, without departing from the scope of the invention.

I claim:

1. In a device of the class described in combination a primary condenser and a secondary condenser, a frame carrying fixed plates of said primary condenser and a fixed armature of said secondary condenser, a shaft journaled in said frame, a hollow shaft rotatably mounted on said shaft and carrying movable plates of said primary condenser, a sleeve fixed to one end of said shaft, a lost motion connection between said sleeve and said hollow shaft, a support frictionally connected to said sleeve and carrying a movable armature of said secondary condenser, stops on said frame for limiting the movements of said movable armature and an adjusting knob for turning said shaft and said hollow shaft.

2. In a device as set forth in claim 1, a setting shaft rotatably mounted in said frame and carrying said adjusting knob, a power transmission disc of small diameter fixed on said setting shaft, another power transmission disc of large diameter fixed on said shaft and driven by said disc of small diameter and a notched disc fixed to said hollow shaft having notches in its periphery in which engages a spring actuated bolt connected to said frame.

3. In a device as set forth in claim 1 a steep helical notch provided on said sleeve and a corresponding means provided in a hub of said support surrounding said sleeve, said means engaging said notch to obtain an axial movement of said support simultaneously with the rotation of said movable plates of the primary condenser.

4. In a device of the class described the combination with a condenser of the rotary type comprising fixed plates mounted in a frame and movable plates fixed on a shaft journaled in said frame and carrying an adjusting knob, of a second condenser comprising a movable and a fixed armature, said movable armature being frictionally connected to said shaft and said fixed armature being mounted on said frame, and stops carried by said frame in a slight distance from each other for limiting the movements of said movable armature, the arrangement being such that during the fine adjustment one of the condensers moves to increase its capacity and simultaneously the other condenser moves to decrease its capacity and vice versa, so as to partially compensate the changes in capacity of both condensers.

5. In a device of the class described the combination with a condenser of the rotary type comprising fixed plates mounted in a frame and movable plates fixed on a shaft journaled in said frame, of a second condenser comprising a movable and a fixed armature, a second shaft jour-

- nalled in said frame frictionally connected to a support for said movable armature, a power transmission disc of small diameter mounted on said second shaft, a power transmission disc of 5 large diameter fixed to said first mentioned shaft and driven by said power transmission disc of small diameter, an adjusting knob fixed to said second shaft for moving the rotatable plates of said rotary condenser as well as said support for 10 said movable armature of said second condenser, and stops carried by said frame at a slight distance apart for limiting the movements of said movable armature, the arrangement being such that during the common operation one of the 15 condensers moves to increase its capacity and simultaneously the other condenser moves to decrease its capacity and vice versa, so as to partially compensate the changes in capacity of both condensers.
- 20 6. In a device of the character described, comprising, a rough adjusting member, a fine adjusting member, coupling means between said rough and fine adjusting members with upper and lower limits to allow of movement of said 25 fine adjusting member between said limits and only within predetermined narrow limits of the range of movement of said rough adjusting member, substantially equally for any position of said rough adjusting member, and a common 30 actuating member for said adjusting members.
7. The combination of a main condenser and a vernier condenser, a first movable element for adjusting the capacity of said main condenser, a second movable element for adjusting the capacity of said vernier condenser, a common actuating member for said condensers, coupling means between said movable elements with upper and lower limits to allow of movement of said second element between said limits and only 35 within predetermined narrow limits of the range of movement of said first element, substantially equally at any position of said first element.
8. The combination of a main rotary condenser and a vernier condenser, said condensers having 40 movable elements for adjusting their capacity, a common actuating member for adjusting said condensers, coupling means between said movable elements with upper and lower limits to allow of adjustment of said vernier condenser between said limits and only within predetermined narrow limits of the adjusting range of said main condenser, substantially equally at 45 any adjusting position of said main condenser, said limits comprising less than 10 angular degrees for a useful adjusting range of 180 degrees of said main condenser.
9. In an adjusting device for a variable condenser or the like, a rough adjusting member, a fine adjusting member, coupling means between 50 said rough and fine adjusting members, said coupling means having a play with upper and lower limits comprising a small fraction of the total useful range of movement of said rough 55 adjusting member to allow of independent movement of said fine adjusting member within said limits and only within predetermined narrow limits of the range of movement of said rough adjusting member, substantially equally for all positions of said rough adjusting member, a common actuating member for said adjusting members, and scale means cooperating with said 60
- actuating member to indicate the position of said actuating member.
10. In an adjusting device for a variable condenser or the like, a rough adjusting member, a fine adjusting member, coupling means between 65 said rough and fine adjusting members, said coupling means having a play with upper and lower limits comprising a small fraction of the total useful range of movement of said rough adjusting member to allow of independent movement of said fine adjusting member within said limits and only within predetermined narrow limits of the range of movement of said rough adjusting member, substantially equally for all positions of said rough adjusting member, an actuating member for said rough adjusting member, and scale means cooperating with said actuating member to indicate the position thereof.
11. In an adjusting device for a variable condenser or the like, a rough adjusting member 20 having a useful range of movement of 180 angular degrees, a fine adjusting member, coupling means between said rough and fine adjusting members, said coupling means having a play with upper and lower limits comprising 10 angular degrees or less to allow of independent movement of said fine adjusting member within said limits and only within predetermined narrow limits of the range of movement of said rough adjusting member, substantially equally for all 25 positions of said rough adjusting member, an actuating member for said rough adjusting member, and scale means cooperating with said actuating member to indicate the position thereof.
12. In an adjusting device for a variable condenser or the like, a rough adjusting member 30 having a predetermined useful range of movement, a fine adjusting member, coupling means between said rough and fine adjusting members, said coupling means having a play with upper and lower limits comprising a range of 1/18th or less of the useful range of movement of said rough adjusting member to allow of independent movement of said fine adjusting member within said limits relative to and only within predetermined narrow limits of the range of movement of said rough adjusting member, substantially equally for all positions of said rough adjusting member, an actuating member for said rough adjusting member, and scale means cooperating 35 therewith to indicate the position thereof.
13. In an adjusting device for a variable condenser or the like, rough adjusting means, fine adjusting means, a common actuating member for both said adjusting means, coupling means 40 between said actuating member and said rough adjusting means having a play with upper and lower limits comprising a small fraction of the total useful range of movement of said rough adjusting means, a frictional coupling connection 45 between said actuating member and said fine adjusting means to allow of independent movement of said fine adjusting means within said limits and only within predetermined narrow limits of the range of movement of said rough 50 adjusting means substantially equally for all positions of said rough adjusting means.
14. In a device as claimed in claim 13, index means of said actuating member, and scale means cooperating therewith to indicate the position of said actuating member.

KARL ERINGEHL
